Primary Examiner—Stella M Reid*Assistant Examiner*—Keli L Hill(74) *Attorney, Agent, or Firm*—Joshua D. Isenberg; JDI Patent(57) **CLAIM**

The ornamental design for a video game controller front face, as shown and described.

DESCRIPTION

The sole FIGURE is a front elevational view of a video game controller front face, embodying our new design.

Portions of the drawings shown in broken lines are environmental structure that is not part of the design. The dot-dot-dash broken lines immediately adjacent the shaded areas represent the bounds of the claimed design while all other broken lines are directed to environment and are for illustrative purposes only; the broken lines form no part of the claimed design.
